UNITED STATES PATENT OFFICE.

THEODORE A. SALA, OF DALLAS, TEXAS.

GAS BURNER.

Application filed August 27, 1927. Serial No. 215,836.

This invention relates to new and useful improvements in gas burners.

The principal object of the invention is to provide a burner having means for pre-heating the air which is admixed with the gas, whereby a more combustible mixture is produced.

Another important object of the invention is to provide means for introducing an auxiliary supply of air to the preheated gas mixture at the point of combustion, whereby a more intense flame is produced and the consumption of gas is reduced as well as fumes substantially eliminated.

Another object of the invention is to provide a preheated chamber in which the air is caused to travel a considerable distance before being mixed with the gas, thus giving it an opportunity to become thoroughly pre-heated.

A further object of the invention is to construct the burner in a number of parts which may, in some forms, be readily cast without the use of cores and which parts may be easily assembled and secured together in a simple manner.

A still further object of the invention is to provide burner units of a simple nature arranged to be readily removed from the burner structure and designed to co-operate in the auxiliary introducing of air.

A construction designed to carry out the invention will be hereinafter described, together with other features of the invention.

The invention will be more readily understood from a reading of the following specification and by reference to the accompanying drawings, in which an example of the invention is shown and wherein:

Fig. 1 is a plan view of the burner assembly constructed in accordance with my invention.

Fig. 2 is a similar view with the upper or top section of the manifold removed.

Fig. 3 is also a plan view, both the top section and the distributor being omitted,

Fig. 4 is a plan view of the lower or bottom section of the burner assembly,

Fig. 5 is a longitudinal vertical sectional view,

Fig. 6 is a transverse vertical sectional view taken on line 6—6 of Fig. 5.

Fig. 7 is a transverse vertical sectional view taken on the line 7—7 of Fig. 5.

Fig. 8 is a plan view of another form in

which the invention may be carried out, a portion of the top section being broken away to show the fuel opening,

Fig. 9 is a plan view of the lower section of the burner assembly,

Fig. 10 is a longitudinal sectional view taken on the line 11—11 of Fig. 8,

Fig. 11 is a longitudinal sectional view taken on the line 11—11 of Fig. 8,

Fig. 12 is a transverse sectional view taken on the line 12—12 of Fig. 8,

Fig. 13 is a transverse sectional view taken on the line 13—13 of Fig. 8,

Fig. 14 is a plan view of the burner assembly,

Fig. 15 is a similar view with the upper section of the manifold removed,

Fig. 16 is a front elevation of the burner assembly,

Fig. 17 is a longitudinal vertical sectional view taken on the line 17—17 of Fig. 14,

Fig. 18 is a transverse vertical sectional view taken on the line 18—18 of Fig. 14,

Fig. 19 is a plan view of the mixing chamber, and

Fig. 20 is an enlarged detail of one of the air introducing bosses and burner units.

In the drawings the numeral 10 designates the lower or bottom section of an elongated manifold. The said lower section has an air inlet opening 11 in one end of its bottom 12, which latter inclines upwardly toward the opposite end and in this latter end is provided a port 13 which may be connected with a suitable gas supply pipe (not shown). The lower section 10 forms the major portion of the manifold in this particular form of the invention and constitutes a preheating chamber.

The lower section has a counter-sunk rectangular shoulder 14 in its upper portion and is also provided with an outwardly directed flange 15 on its top. A flue member comprising a rectangular plate 16 and a flue 17 is seated on the shoulder 14. The flue 17 extends longitudinally of the lower section or chamber 10 and inclines downwardly toward the port 13, its lower end being open and its upper end closed. By observing Figs. 6 and 7, it will be seen that a passage 105 is provided along each side and under the flue.

A distributor or plate 18 rests upon the plate 16 and is provided with an upstanding distributing head 19 disposed over the upper 110

closed end of the flue 17. A concaved boss 20 inclining downwardly from the head depends on the under side of the plate 18 so as to hang in the top of the flue 17. When the burner assembly is in operation, gas will be supplied through the port 13 and being under pressure will be directed into the flue 17. Air will be drawn in through the opening 11 and caused to travel along the passages along each side and under the flue 17. This air upon reaching the open end of the flue will be drawn thereinto and mixed with the gas. The heat from the burner will cause the walls of the flue, the boss 20, the plate 18 and the head 19 to become hot. Thus, the air will be preheated as it travels along the outside of the flue and the mixture of air and gas will be heated while traveling through said flue.

20 A top or upper section 21 fits over the head 19 and rests upon the plate 18 within the opening at the top of the preheating chamber 10. The head 19 is preferably made flat so that the top section will fit thereover 25 and the flange 15 surrounds the top section, thus holding it against lateral displacement. The head 19 is provided with a plurality of ports 22, 23 and 24 respectively. These ports are given such diameters as to properly distribute the gaseous mixture, this being necessary because the head is located nearer one end of the top section 21. The ports 23, which are on each side of the head, may be of the same diameter and the port 22 30 may be of a like diameter or it may be of a different diameter if found advantageous. The port 24 is made considerably larger so as to provide a generous supply of the mixture for that portion of the top section extending therefrom.

40 One of the important features of the invention resides in burner units constructed to admit an auxiliary supply of air to the preheated gas mixture, one of such units being shown in detail in Fig. 20. The top section 21 is provided with a plurality of up-standing tubular bosses or burners 25 connected with the manifold through ports 26. These burners may be suitably arranged. Satisfactory results have been had with a double row of the same, as is shown in Fig. 45 1. Each burner has a plurality of vertical air inlets or louvers 27. In the lower portion of each burner is provided an internal annular shoulder or seat 28 below the louvers, while another internal annular shoulder 29 is provided at the top above the louvers.

50 In each boss is disposed a mixing unit 30 and each unit comprises a top disk 31 resting on the shoulder 29 and a bottom disk 32 resting on the shoulder 28. Spaced vertical tubes 33 extending through and fastened in these disks project above and below the same. The top disk 31 has perforations 34 55 between the tubes. Each mixing unit may

be made to drop into the boss so that the disk 32 resting upon the shoulder 28 will close the port 26, while the top disk 31 resting on the shoulder 29 will close the top of the boss. It is to be understood that the bosses will be comparatively small and the tubes even smaller. The mixing units may be readily removed for cleaning and are easily placed in assembling the structure.

55 The gaseous mixture, which has been thoroughly preheated in flowing through the chamber 10, flue 17, and escaping through the ports of the head 19 into the top section 21, will be heated to a greater extent as it flows through the said top section 21 and 60 escapes through the ports 26. This mixture will pass upward through the tubes 33. Auxiliary air will be drawn in through the louvers 27 and will pass upward through the perforations 34, thus further admixing 65 air and promoting economical combustion in the flame which is burning above the unit 30. This generous supply of air will greatly reduce the fuel consumption and not only assure a more perfect combustion 70 but will tend to eliminate fumes.

75 In Figs. 8 to 13, I have shown another form in which the invention may be carried out. A bottom section 40 includes a longitudinal preheating chamber 41 having an air inlet opening 42 at one end, as is best shown in Figs. 9 and 10. The bottom chamber inclines upwardly and opens into a longitudinal flue 43 which inclines upwardly 80 toward the air-admitting end of the section. The chamber and the flue are substantially parallel, being separated by a partition wall 44, as is illustrated in the several figures. The chamber 41 is quite similar to the chamber 10 previously described, while the flue 43 is similar to the flue 17. A port 44' is provided at the front end of the flue 43 for receiving a gas supply pipe 45. Gas supplied under pressure is directed into the flue 43 and air drawn into the opening 42 is 85 pulled along the chamber 41 and mixed with the gas in the flue 43.

90 The lower section 40 has a comparatively flat top surface and is provided with a marginal sealing groove 46 which has a branch 47 extending along the top of the wall 44. An intermediate member 48 has a flat under surface and is provided with a depending sealing bead 49 fitting in the groove 46 and provided with a branch 50 fitting in the groove 47. The member 40 is provided with ears 51, while the member 48 has registering ears 52 so that bolts 53 passed through said ears will fasten the parts together, the beads and grooves preventing the escape of products from between the members.

95 The member 48 has a fuel discharge opening 54 extending from the upper end of the flue 43 and preferably inclined to direct the gaseous mixture into an upper section 55. 100

The section 55 has a depending marginal bead 56 fitting in a sealing groove 57 on top of the member 48. It will be noted that the member 48 has a concaved hood 58 overhanging and forming the upper portion of the flue 43. This hood inclines as does the flue so as to permit a free escape of the gaseous mixture at the upper end of the flue. The air and the gaseous mixture are, of course, preheated in the chamber 41 and the flue 43 in the same manner as in the form previously described. The top member 55 is equipped with burner bosses and units the same as are shown in Fig. 20 and further description of the same is unnecessary.

In Figs. 14 to 19 still another form of the invention is set forth. In this form 60 designates the intermediate section and 61 the upper or top section of an elongated manifold. The lower section has a rectangular sealing groove 62 in a horizontal plane adapted to receive a rectangular bead 63 depending from the lower edge of the section 61. A lower section or preheating chamber 64 has a horizontal marginal groove 65 in its upper edge receiving a complementary bead 66 depending from the bottom of the section 60. The chamber also has a pair of forwardly directed grooves 67 in the upper edges of baffle walls 68 receiving beads 69 depending from the section 60.

It will be seen that the structure comprises three main elements, each of which may be easily cast without the use of cores. On each side at its front, the chamber 64 is provided with ears 70 underlying ears 71 of a hood 72 formed integral with and projecting from the section 60 over said chamber. Bolts 73 passing through the said ears secure the chamber and the hood together. The chamber, near its rear, has ears 74 on each side receiving bolts 75 passing down through the sections of the manifold, as is shown in Fig. 17 whereby the units of the assembly are fastened together. It will be seen that by the use of four bolts the entire structure may be securely fastened together ready for use.

The chamber 64 comprises comparatively deep forwardly directed air passages or channels 76 arranged on each side and each having an air admitting port 77 in its bottom at the rear end. These flues are disposed horizontally on each side of the baffle walls 68 and between the baffle walls is a rearwardly directed mixing flue 78. By observing Fig. 18 it will be seen that the passages 76 incline upwardly and forwardly while the flue 78 inclines upwardly and rearwardly.

As is best shown in Fig. 19, the baffle walls 68 terminate short of the front wall of the chamber and each air channel converges toward its forward end discharging into the front end of the mixing channel 78 through a reduced throat 79. The hood 72 has a central dome 80 arching over the mixing flue 78.

A lip 81 depends from the front end of the dome and fits in a sump 82 in the front of the chamber. A gas cock 83 is screwed into an aperture 84 in the lip and is also fastened on the end of a gas supply pipe 85.

It will be seen that gas discharged from the gas cock 83, which may be of the usual construction, will be directed rearwardly and upwardly in the channel 78 whereby air will be drawn into the passages 76 through the ports 77. When the burner is in operation, the whole structure will be heated and thus the walls of the chamber 64 will become hot. The air, in passing forwardly in the passages 76, will be preheated before discharging through the throats 79 into the mixing flue 78. By this arrangement a more combustible gaseous mixture will be produced.

The manifold section 60 has a central opening or port 86 overhanging the rear end of the flue 78 which is curved upward toward said port. The dome 80 is continued into the manifold section, as is shown in Figs. 15 and 18, so as to increase the preheating operation, it being understood that the hood 72 co-acts with the chamber in heating the air and gaseous mixture. It will be seen that the manifold section 60 inclines upwardly from the port 86 toward each end. The top section 61 of the manifold is provided with the burner bosses 27 and ports 26 the same as in the other forms.

Various changes in the size and shape of the different parts, as well as modifications and alterations, may be made within the scope of the appended claims.

What I claim is:

1. In a gas burner, the combination of a bottom manifold section, a top manifold section having burner outlets, a preheating chamber connected with the bottom section, and an intermediate section between the top and bottom sections having an opening for supplying the gaseous mixture to the top section, the preheating chamber having an air passage, and a mixing flue contiguous to the air passage extending from the chamber to the intermediate section.

2. As a sub-combination in a gas burner, a top section having burner outlets, under sections attached to the top section and supplying a mixture of air and gas thereto, burner bosses extending upwardly from the top section and surrounding the burner outlets, said bosses having auxiliary side air inlets, and mixing units comprising opposite plates connected by conductors and removably seated within the bosses for conducting the gaseous mixture through the bosses and mixing it with the auxiliary air at the tops of the said bosses.

3. As a sub-combination in a gas burner, a top section having burner outlets, under sections attached to the top section and supplying a mixture of air and gas thereto,

burner bosses extending upwardly from the top section and surrounding the burner outlets, said bosses having auxiliary air inlets at their sides, and mixing units comprising 5 opposite plates seated within the bosses and sealing them above and below their air inlets, said units having gas conductors extending between said plates and air escape ports in the upper plate near the upper ends 10 of said conductors.

4. In a gas burner, a bottom section including a preheating chamber having an elongated air passage provided with an air admitting port at its rear end, a mixing flue 15 comprising in part a separable section seated upon the preheating chamber and communicating at its forward end with the forward end of the chamber air passage and also having a gas supply at its forward end, 20 an intermediate section into which the mixing flue discharges, and a top section mounted on the intermediate section and having burner outlets communicating with the intermediate section, the air and gaseous 25 mixture passing through the chamber and flue being preheated by the hot burner parts.

5. In a gas burner, a bottom section including a preheating chamber having an elongated air passage provided with an air admitting port at its rear end, a mixing flue 30 comprising in part a separable section seated upon the preheating chamber and communicating at its forward end with the forward end of the chamber air passage and 35 also having a gas supply at its forward end, an intermediate section into which the mixing flue discharges, and burner bosses on the

top section connected with the burner outlets and having auxiliary air admitting openings.

6. In a gas burner, a manifold comprising 40 separable sections seated upon each other, the upper section having burner outlets and a gas inlet, a lower section including a pre-heating chamber inclined downwardly from a gas supply inlet at one end thereof to an 45 air supply inlet at its opposite end, and a mixing flue within the lower section inclined upwardly from the gas supply to the gas inlet of the upper section.

7. In a gas burner, a combined lower section and preheating chamber having an air passage, a gas mixing flue within said section, the air passage of the chamber having an inlet port at one end and communicating with the mixing flue at its opposite end, a gas 55 inlet at the point of such communication, and a separable top burner section spaced above the outlet from mixing flue.

8. In a gas burner, a burner section, a pre heating section formed with an air inlet 60 chamber, a mixing flue disposed within the preheating section and having a gas supply inlet at one end and communicating at its opposite end with the burner section, said inlet chamber having an air passage extending along one side of the mixing flue and communicating therewith at its gas inlet end, said air passage having an air admitting port at its opposite end, whereby said air passage and flue are directly associated 65 within the preheating section.

In testimony whereof I affix my signature.

THEODORE A. SALA.
